UNITED STATES PATENT OFFICE.

CYRUS WHISLER, OF BRIGHTON, IOWA, ASSIGNOR OF ONE-HALF TO J. F. HODGEN, OF SAME PLACE.

WASHING-MACHINE.

SPECIFICATION forming part of Letters Patent No. 321,329, dated June 30, 1885.

Application filed April 28, 1884. (No model.)

To all whom it may concern:

Be it known that I, CYRUS WHISLER, a citizen of the United States, residing at Brighton, in the county of Washington and 5 State of Iowa, have invented certain new and useful Improvements in Washing-Machines; and I do declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 Figure 1 of the drawings is a vertical sectional view of my device, and Fig. 2 is a transverse sectional view of the same.

This invention has relation to washing-machines; and it consists in the construction and 20 novel arrangement of devices, as hereinafter set forth, and pointed out in the appended claim.

In the accompanying drawings, the letter A designates the water box or tub, which is 25 of elongated form, having parallel sides B, in the upper portion of which are provided bearings C for the journals of the swinging rubber.

The rubber D consists of the barred end 30 frames, E and F, having journals g g, upon which they swing, a barred bottom frame, H, pivoted at its ends to the lower portions of the end frames, and a loose barred frame, J, having projecting ends k, adapted to be inserted between the bars of the swinging frames E and F.

The rubber is constructed as follows: To 35 form the end frames the upright bars a are placed parallel to each other, and are connected to the transverse journal-rod b, washers c being placed on the rod between the bars. At their lower ends the bars a of each frame are connected by transverse pivot-rods d, upon which are also pivoted the ends of the bottom bars, e, which are parallel to each other, and in the intervals between the bars a. These bottom bars connect the lower portions 45 of the upright frames E and F, and form a rack on which the clothes are placed. The bottom bars are notched at intervals, as shown at v.

An upper rack, J, or pressure-frame, of similar form to the bottom rack, is made of parallel bars l, which are connected by transverse rods m. The ends k of these bars project beyond the rods m, and are designed to be seated between the bars a of the end frames in the interspaces s. The bars of the frame J are notched on the under side, as indicated, the notches of the bars l and e alternating with each other. The notches of the upper rack-frame, J, and of the lower frame, H, are designed to afford purchase whereby these racks may hold to the articles placed between in the washing operation.

The side bars of the end frame E are extended above the top of the tub and provided with a cross-bar, Z, to form an operating-handle.

The action of this rubber is a longitudinal 70 swinging motion, which moves the articles to and fro in the water, and at the same time up and down. The leverage of the end frames upon the loose rack moves it backward as the rubber swings forward, so that a continuous 75 reciprocating rubbing movement on the goods is kept up between the loose rack and the bottom rack. The leverage of the end racks also compresses the loose rack toward the bottom rack at each end alternately as the 80 rubber swings back and forth, inducing a swinging action on the goods, which materially facilitates the cleansing operation.

Having described this invention, what I 85 claim, and desire to secure by Letters Patent, is—

The combination, with the elongated tub having the journal-bearings C, of the swinging barred end frame E, extended to form a handle, the swinging barred end frame F, the 90 parallel barred bottom pivoted to the end frames, and the parallel barred loose pressure-frame J, having its ends seated in the intervals between the bars of the end frames and the adjacent sides of the bars e and l, having 95 notches, substantially as specified.

In testimony whereof I affix my signature in presence of two witnesses.

CYRUS WHISLER.

Witnesses:

ALFRED WHISLER,
E. O. BENNETT.
